(57) **CLAIM**

The ornamental design for a battery service cart, as shown and described.

DESCRIPTION

FIG. 1 is a top, left, front perspective view in a partially open configuration showing my new design, shown in a condition of use;

FIG. 2 is a top, left, front perspective view in a partially open configuration, thereof;

FIG. 3 is a top plan view in a partially open configuration, thereof;

FIG. 4 is bottom plan view in a partially open configuration, thereof;

FIG. 5 is a front elevation view in a partially open configuration, thereof;

FIG. 6 is a back elevation view in a partially open configuration, thereof;

FIG. 7 is a left side elevation view in a partially open configuration, thereof;

FIG. 8 is a right side elevation view in a partially open configuration, thereof;

FIG. 9 is a top, left, front perspective view in a fully open configuration, thereof;

FIG. 10 is a top plan view in a fully open configuration, thereof;

FIG. 11 is bottom plan view in a fully open configuration, thereof;

FIG. 12 is a front elevation view in a fully open configuration, thereof;

FIG. 13 is a back elevation view in a fully open configuration, thereof;

FIG. 14 is a left side elevation view in a fully open configuration, thereof;

FIG. 15 is a right side elevation view in a fully open configuration, thereof;

FIG. 16 is a top, left, front perspective view in closed configuration, thereof;

FIG. 17 is a top plan view in a closed configuration, thereof;

FIG. 18 is bottom plan view in a closed configuration, thereof;

FIG. 19 is a front elevation view in a closed configuration, thereof;

FIG. 20 is a back elevation view in a closed configuration, thereof;

FIG. 21 is a left side elevation view in a closed configuration, thereof; and,

(Continued)

FIG. 22 is a right side elevation view in a closed configuration, thereof.

The broken lines in FIG. 1 illustrate environmental structure which forms no part of the claimed design.
